HOUSING FOR AN ANAMORPHOSER

Robert E. Gottschalk and John R. Moore, Los Angeles, Calif., assignors to Panavision, Inc., a corporation of California

Application January 17, 1955, Serial No. 34,008

Term of patent 14 years

(Cl. D57—1)

FIG. 1.

FIG. 2.

FIG. 4.

FIG. 3.

Figure 1 is a perspective view of the housing for an anamorphoser embodying our design;

Fig. 2 is a side elevational view of the housing;

Fig. 3 is a front elevational view in the direction indicated by the arrow 3 of Fig. 2; and

Fig. 4 is a rear elevational view in the direction indicated by the arrow 4 of Fig. 2.

We claim:

The ornamental design for a housing for an anamorphoser, as shown.
